F. COWAN

DOORCHECK

Filed June 10, 1927

Frank Cowan
INVENTOR
BY Victor J. Evans
ATTORNEY

UNITED STATES PATENT OFFICE.

FRANK COWAN, OF ROCHESTER, MINNESOTA.

DOORCHECK.

Application filed June 10, 1927. Serial No. 197,917.

This invention relates to door checks and the general object of the invention is to provide a device of the character set forth having means arranged in the path of a door and 5 cooperating with relative means for retarding the closing of the door so as to prevent slamming thereof but allowing the door to close gently with minimum sound and vibration.

10 A further object of the invention is to provide a door check that is easy to apply, extremely simple in construction, inexpensive to manufacture, is strong and sturdy, and efficient in operation and service.

15 This invention also consists in certain other features of construction and in the combination and arrangement of the several parts, to be hereinafter fully described, illustrated in the accompanying drawings and specifically 20 pointed out in the appended claims.

In describing my invention in detail, reference will be had to the accompanying drawings wherein like characters denote like or corresponding parts throughout the several 25 views, and in which:

Figure 1 is a fragmentary perspective view illustrating the application of my check to the frame of a door.

Figure 2 is a face view of the check per se 30 with the cover removed and showing the parts in normal position.

Figure 3 is a similar view with the parts in operative position and showing the door in dotted lines.

Figure 4 is a sectional view taken approximately on line 4—4 of Figure 2.

The case 1, and the cover 2, constitute the casing in which my check mechanism is housed. Upon the pin 4, is pivotally secured 40 a hanger 5, at the lower end of which is suspended a balanced catch 8, pivoted on a pin 9. The catch 8 is shown as being substantially rectangular in formation and the pin 9 extends through a depending projection of the 45 hanger and through the side walls of the catch which is provided with a reduced end shaped to give the catch a substantially pawl like form. Below the balanced catch is a curved block 10, into which notches are cut 50 on its upper surface. The device is attached

to the door jamb 11 by means of screws 3 and the door stop 13 is cut away to permit the casing to be fastened to the jamb 11, flush with the stop 13.

55 The hanger 5 swings free on the pin 4, and sufficient clearance is provided between the

balanced catch 8 and the block 10, to permit the hanger 5, to be pushed back, flush with the rear wall of the casing 1, if done slowly so as to not cause the catch to swing on its pivot. The catch 8 is however so balanced that when the door 12 is slammed against an arm 14 which normally extends through an opening formed in the casing and is included in the hanger 5, the inertia of the balanced 60 catch 8, impels it to dip and thereby catch the reduced end in the notches in the block 10 and stop the door before it slams against the door stop 13. Upon the rebound, the hanger 5 and the balanced catch 8, swing back 65 to original position and when the door 12 is gently closed against it, the reduced end passes the notches in the block 10, without engaging and the door closes against the stop 13, 13. An arm 15 is also included in the 70 hanger and extends rearwardly in opposed relation with respect to the arm 14. The arms may have their ends grooved as at 16, to accommodate the tongues 17 of rubber facings 18, which are secured to the arms by the 75 tongue and groove connections as shown. The arms are slightly tapered and together with the portion which receives the pin 4 gives the hanger the form of an inverted T.

I claim:

1. A door check of the character described comprising a casing having an opening formed therein, a hanger pivotally secured in said casing, means formed with said hanger and normally arranged through said opening to be arranged in the path of a door, notched means arranged in said casing and means pivotally secured to the hanger and cooperating with the notched means.

2. A door check of the character described comprising a casing, a substantially T-shaped hanger arranged in inverted position therein, means for pivotally securing the hanger in said casing, a depending projection included in said hanger, a catch pivotally secured to the projection, a block arranged in said casing below the catch and being provided with notches cooperating with said catch, and said casing being provided with an opening to accommodate a portion of said hanger for the purpose specified.

3. A door check of the character described comprising a casing, a hanger pivotally secured in said casing, opposed arms included in said hanger and being provided with grooves in their ends, resilient means secured in said grooves, a projection included in said

hanger, a catch pivotally secured to said projection and having a reduced end, a notched block secured in said casing and being arranged for disposing the notches thereof for cooperation with the reduced end of the catch, and one of said arms being arranged for passage through an opening formed in said casing.

4. A door check of the character described
10 comprising a casing, an inverted substantially

T-shaped hanger pivotally secured in said casing and including means for passage through an opening in said casing, means for securing said first mentioned casing in a manner whereby said means is arranged in a 15 path of a door, a notched block arranged in said casing and means carried by said hanger for cooperation with the notches in said block.

FRANK COWAN
